(57) **CLAIM**

The ornamental design for the stand-up red light therapy device, as shown and described.

DESCRIPTION

FIG. 1 is a front right perspective view of a stand-up red light therapy device showing the new design.

FIG. 2 is an enlarged view thereof of portion 2 shown in FIG. 1.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

The short dashed lines in the drawings depict portions of the stand-up red light therapy device that form no part of the claimed design. The dot-dash broken lines depict the bounds of the enlarged view and form no part of the claimed design.
